UNITED STATES PATENT OFFICE

ADOLPH G. LOTTER, OF MILWAUKEE, WISCONSIN, ASSIGNOR TO STATIONERS LOOSE LEAF COMPANY, OF MILWAUKEE, WISCONSIN, A CORPORATION OF WISCONSIN

LOOSE LEAF BINDER

Application filed September 17, 1930. Serial No. 482,394.

This invention relates to certain new and useful improvements in loose leaf binders of the type illustrated in Patent No. 1,777,006, dated September 30, 1930, and commonly used with visible record systems in which the leaves are so arranged in the binder that their lower and upper edges are staggered to permit data on the upper portion of the leaves to be visible at all times.

10 In visible record systems, it is frequently necessary to insert or remove leaves from the book, in which case it is necessary to shift some of the leaves to maintain their staggered relation at all times. Numerous devices for 15 accomplishing this result have been proposed, but these are either expensive to manufacture or do not provide the desired flexibility in the insertion or removal of the leaves, and therefore, this invention contemplates as an 20 object the provision of an improved binder for use with visible record systems which has great flexibility as to its ability to shift one or more leaves in either direction to accommodate the removal or insertion of other leaves. 25 Another object of this invention resides in the provision of an improved binder of the character described, which is so constructed mechanically as to be easily operated and which will not be readily damaged by the 30 rough handling to which devices of this character are normally subjected.

Heretofore binders adapted for use with visible record systems have had their series of impaling prongs staggered with respect to each other by longitudinally shifting either one or both series and this invention has as a further object the provision of an improved manner of mounting the impaling prongs whereby they are tilted about transverse axes to stagger their adjacent ends and facilitate shifting of the leaves.

And a more specific object of this invention resides in the provision of novel means for mounting the impaling prongs of one series for rocking movement about transverse axes adjacent their inner ends and longitudinally shiftable means for simultaneously rocking the impaling prongs to tilt their outer ends 50 out of normal position into staggered rela-

tion with the ends of the impaling prongs of the other series.

With the above and other objects in view which will appear as the description proceeds, my invention resides in the novel construction, combination and arrangement of parts substantially as hereinafter described and more particularly defined by the appended claims, it being understood that such changes in the precise embodiment of the 55 hereindisclosed invention may be made as come within the scope of the claims.

In the accompanying drawings, I have illustrated two complete examples of the physical embodiment of my invention constructed 60 according to the best modes I have so far devised for the practical application of the principles thereof, and in which:

Figure 1 is a top plan view of a binder embodying this invention with the covers in 65 open position, and with portions broken away to illustrate structural details;

Figure 2 is a view similar to Figure 1 with the covers removed and with the impaling prongs separated and tilted to staggered 75 position;

Figure 3 is an enlarged longitudinal sectional view taken through Figure 1 on the plane of the line 3-3;

Figure 4 is a view similar to Figure 3 80 taken through Figure 2 on the plane of the line 4-4;

Figure 5 is a transverse sectional view taken through Figure 1 on the plane of the line 5-5;

Figure 6 is a detail perspective view of the elements for mounting and shifting the series of tiltable impaling prongs, the parts being separated but arranged in their proper order of assembly;

Figure 7 is a view similar to Figure 2 of a slightly modified form of this invention;

Figure 8 is a view similar to Figure 5 of the modification illustrated in Figure 7;

Figure 9 is an enlarged transverse sectional view taken through Figure 7 on the plane of the line 9-9;

Figure 10 is a fragmentary detail view taken through Figure 9 on the plane of the line 10-10; and

Figure 11 is a detail perspective view of one of the elements of the structure illustrated in Figure 7.

Referring now more particularly to the accompanying drawings, in which like numerals designate like parts throughout the several views, 5 represents a loose leaf binder back plate having covers 6 and 7 hinged to its opposite edges as at 8, the back plate being preferably formed with its marginal edges 9 directed inwardly and having a base plate 10 extending across the marginal edges, the base plate being fixed to the back plate by rivets 11 or the like.

15 The base plate 10 has a lazy tong device mounted thereon which consists of a pair of intersecting levers 12 and 13 pivotally connected at their point of intersection by a rivet or pin 14 passing therethrough and through the back plate, base plate and a slidably mounted latch or locking member 15 to be later described. The pin 14 is riveted over the back plate and the latch member 15 and the aperture 17 of the latch member through which the pin 14 passes is elongated to permit limited longitudinal movement of the latch member.

A pair of smaller levers or links 18 and 19 having their outer ends pivotally connected, as at 20, is connected with the levers 12 and 13 at each side of their pivotal connection 14, by rivets 21 or the like, passing through the inner ends of the levers 18 and 19 and through the levers 12 and 13, at points equi-spaced from the pivot pin 14, the pivots 20 passing through elongated apertures (not shown) in the base plate 10 to guide their movements and insure the movement of the adjacent ends of levers 12 and 13 in the same plane, as will be readily apparent.

The ends of levers 12 and 13 are pivotally connected with a pair of sidewise movable elements or slide plates 23 and 24 by rivets 25 that pass through elongated apertures 26 in the levers 12 and 13 to provide the necessary play. The sidewise movable elements or slide plates are thus maintained parallel during their movement towards and away from each other by the lazy tong device.

50 Both slide plates are slightly shorter than the base plate 10 and are guided for movement thereover by upwardly and inwardly directed flanges 27 and 28 respectively, at the opposite ends of the base plate, and are maintained spaced from the base plate by downwardly extended transverse beads or ribs 29 formed at each end of the slide plates, the height of the beads or ribs being sufficient to accommodate the combined thickness of the levers forming the lazy tong device.

Two series of cooperating impaling prongs or ring members 30 and 31 are associated with the sidewise movable elements or slide plates 23 and 24 respectively. The prongs

of the series 30 are stationary with respect to the slide plate 23 and are welded or otherwise secured, as at 32, to a cover plate 33, which is connected with but spaced from the slide plate 23 by shouldered rivets 34, and has its outer marginal edge flanged downwardly as at 35 to provide a neat external appearance.

70 The prongs of the series 31 are adapted for a rocking or tilting movement about transverse axes adjacent the slide plate 24, being secured, as by welding, to individual plate members 36 which have a rocking connection with the sidewise movable element 24, now about to be described.

75 The plate members 36 are of a configuration best illustrated in Figure 6 and are received in depressions 37 formed in two adjacent plates 38 and 39 which are secured one above the other on the slide plate 24. The plates 38 and 39 are thus rigid with the sidewise movable element or slide plate 24. The depressions 37 in which the plate members 36 are situated are of a depth equal to the combined thickness of the plates 38 and 39 and are provided with notches 40 which are formed only in the plate 38.

80 The notches 40 are directly opposite each other and receive lugs 41 and 42 extended from the ends of the plate members 36 to support the plate members above the bottoms of their respective depressions 37, so that the plate members 36 form substantially continuations of the outer plate 38. Besides the notches 40, the plate 38 also has notches 43 communicating with the depressions 37 to receive lateral extensions 44 on the plate members 36.

85 The lugs 41 and 42 form trunnions about which the plate members 36 and the impaling prongs carried thereby may be rocked, and when the plate members are in their normal positions with their impaling prongs in upright positions, the extensions 44 are received in the notches 43.

90 All of the several plate members 36 are loosely set in their respective depressions 37 and are held therein by a longitudinally shiftable plate 45 connected by means of rivets 46, with the sidewise shiftable element comprising the plates 24, 38 and 39, the rivets 46 passing through elongated openings 47 in the plate member 45 to permit longitudinal shifting thereof.

95 Openings 48 in the plate 45 accommodate the extension of the prongs 31 thereabove and cooperate, in a manner to be later described, with certain elements of the plate members 36 upon longitudinal shifting of the plate 45, to rock or tilt the plate elements simultaneously about the axis of their lugs 41 and 42.

100 Each of the prong-carrying plate elements 36 has a hook-like element 49 projecting above its top surface a distance equal to substantially the thickness of the plate 45 at a point

diagonally opposite its extension 44, and each of the plate elements also has a rivet head or other suitable projection 50 extending upwardly from its top surface at a point forwardly of the base of its prong 31.

When the plate 45 is in its normal position of longitudinal adjustment, as illustrated in Figure 1, the projections 50 of the plate members 36 are in line with portions 51 of the openings 48 and projections 52 extended from one corner of the portions 53 of the openings 48 are engaged beneath the hook-like elements 49 so that the plate members 36 are substantially interlocked with the plate 45 and are thus held in their proper normal positions with their prongs 31 in alignment with the prongs 30. To facilitate the engagement of the projections 52 beneath the hook-like elements 49, the top surface of the projections is preferably beveled as illustrated.

Longitudinal shifting of the plate 45 to its position illustrated in Figure 2, simultaneously rocks all of the plate members 36 about the axis of their trunnions 41 and 42 in the following manner: As the plate 45 is shifted to the left from its position illustrated in Figure 3, to that of Figure 4, the projections 52 move from beneath the hook-like elements 49 and the edges 54 of the portions 51 of the openings 48 in the plate, ride onto the projections 50 and consequently tilt or rock the plate members to swing the free ends of their prongs to the positions illustrated in Figure 2. During this movement of the plate members 36, their extensions or tail pieces 44 rise above the plane of the plate 38, such movement on the part of the extensions 44 being accommodated by apertures 55 in the plate 45.

Inasmuch as the lugs 41 and the portions 40 of the plate members 36 forming extensions of the lugs 42 are at all times positioned beneath the plate 45 irrespective of its position of adjustment, the upper portions of the lugs 41 and said parts of the plate member are beveled as best illustrated in Figure 6 to permit the tilting or rocking of the plate members 36 about the axis of their lugs 41 and 42.

It is noted that when the plate 45 is in its position of adjustment illustrated in Figure 50 2, the edges 54 of the openings 48 are substantially in alignment with the center of the projections 50, and as the plate 45 is returned to its normal position the prong-carrying plate members 36 are returned to their normal positions by the engagement of the edges 56 of the openings 55 with the top surface of the plate member tail pieces or extensions 44. This engagement rocks the plate members into their normal positions parallel with the plate 55 38 so that the extensions 52 are enabled to ride beneath the hook-like elements 49 to thus again substantially interlock the plate 45 with the elements 36 and thus form a rigid mounting for the prongs 31.

The plate 45 it is noted, has its outer mar-

ginal edge directed downwardly as at 57 similar to the downwardly directed edge 35 of the plate 33 to provide a symmetrical external appearance for the structure, and one end thereof has an offset extension 58 which as

best illustrated in Figures 3 and 4, is in a plane above the adjacent portion 28 of the base plate 10. A stud 59 extends upwardly from the offset extension 58 to afford convenient means for shifting the plate 45 longitudinally to effect the rocking or tilting of the series of impaling prongs 31 and the bottom end 60 of the stud 59, which is reduced in diameter, extends downwardly from the extension 58 to cooperate with a finger 61 on the adjacent fixed flange 28 and provide a releasable lock for holding the plate 45 against longitudinal shifting when the two series of prongs are closed onto each other. The stud extension 60 extends slightly beneath the plane of the flange 28 and is received in a recess 62 formed in the plate 38.

Extending upwardly from the plate 33 which carries the series of impaling prongs 30, is a second stud 63 similar to the stud 59 which cooperates with the stud 59 to provide convenient means for manually shifting the two series of prongs toward and away from each other and to accommodate the stud 63, the flange 28 is cut away as at 64.

When the sidewise shiftable elements and their associated series of prongs are closed onto each other by moving the studs 59 and 60 to their positions illustrated in Figure 1 and the binder is said to be in closed position, it may be secured in said position by means of the locking member 15. This member, as hereinbefore stated, is mounted for longitudinal shifting with respect to the base plate by the rivet 14 and similar rivets 14' operating in elongated slots 17' in the locking member 15.

The locking member 15 cooperates with the raised tongues 65 struck from the inner edges of the cover plate 33 and the plate 38 to secure the prong-carrying sections against separation. To effect this cooperation, the tongues are adapted to be engaged in locking recesses 66 at one end of raised portions 67 in the locking member 15, the raised portions 67 being of a height to permit the tongues 65 to pass therebeneath when the member is shifted to unlocked position.

The specific operation of the locking member is shown and described at length in the said patent hereinbefore referred to and reference may be had thereto for a detail description thereof.

When it is desired to effect the shifting of one or more leaves, the binder is opened as illustrated in Figure 1 and the locking member 15 is operated to release the mechanism for opening by depressing its end 68 to disengage the lugs 69 carried thereby from the head 70 of the adjacent rivet 14', and moving

it downwardly with respect to Figure 1. This movement of the locking member 15 aligns the tongues 65 with the raised portions 67 and thus releases the slide plates 23 and 24 with which the prongs 30 and 31 are associated for sidewise movement.

The studs 59 and 63 are then grasped and moved apart to separate the series of prongs and disengage the stud end 60 from the finger 61. The plate 45 may be then shifted longitudinally by means of its stud 59 to rock or tilt the series of prongs 31 to their positions illustrated in Figure 2. The studs 59 and 63 are then moved toward each other so that the ends of the prongs, when they reach their fully closed positions, are in staggered relation to facilitate the transfer of leaves from one series of prongs to the other without disturbing their staggered relation. When in this position the stud end 60 engages its cooperating finger 61 on its inner surface and secures the plate 45 against longitudinal shifting, and if desired the binder may be locked in this position by moving the member 15 upwardly with respect to Figure 2 to re-engage its locking recesses 66 with the tongues 65. After the sheets have been shifted as desired, the binder is again unlocked, the prongs separated and the plate 45 actuated to re-align the ends of the prongs 31 with those of the prongs 30.

In Figures 7 to 11 inclusive, a slightly modified mechanism is illustrated for accomplishing the same movement on the part of the series of prongs 31, as described in connection with the disclosure of Figures 1 to 6 inclusive. In this instance, all of the mechanism for guiding the prong-carrying elements for sidewise movement is identical with that hereinbefore defined, and the only difference is in the specific mounting for the prongs 31 and the means for rocking them to swing their outer ends into and out of alignment with the ends of the prongs 30. This difference however, permits a more symmetrical external appearance as the entire mechanism for effecting the tilting of the prongs is enclosed and out of view.

Referring now specifically to Figures 7 to 11, the plate 24 has a strip 71 riveted thereto, which, as best illustrated in Figure 11, is struck from bendable metal to form straps 72 engageable over the innermost ends 73 of the prongs 31 which are straight and directed at an angle to their major portions to lie flat on the upper surface of the plate 24. The straps 72 thus form bearings in which the prong ends 73 are rotatably mounted, and to secure the prongs against axial shifting in their bearings, their extreme inner ends 74 are directed downwardly at right-angles to their portions 73, to extend through openings 75 in the plate 24 and into elongated openings 76 in a shift bar 77. The openings 75 are sufficiently large to permit the desired

motion on the part of the prong ends 74 and the openings 76 are of a width to snugly engage the same at opposite sides to hold the prongs against axial shifting in their bearings.

At the ends of the bearings provided by the straps 72 opposite the ends at which the prong ends 74 are disposed, the upper portion of the straps is cut away as at 78 to provide shoulders 79 at right-angles to the plate 24 which shoulders form abutments against which the adjacent upwardly extending portions of the prongs 31 engage to limit the rocking motion of the prongs in one direction. In the other direction the rocking movement of the prongs is limited by the engagement of their ends 74 with the right-hand ends of the elongated openings 76 in the bar 77, see Figure 9.

It is noted that the travel of the longitudinally shiftable bar 77 is considerable. This necessitates the elongation of the openings 76 and a degree of lost motion during operation of the prongs, but permits a more desirable construction of locking means for securing the bar 77 against longitudinal motion. This, as in the structure illustrated in Figures 1 to 6 inclusive, comprises an extension 60' on the bottom of stud 59' carried by the bar 77 and a finger 61' which in this instance however, is formed in the base plate 10 and is therefore not exposed to view. The limits of longitudinal travel of the bar 77 are defined by the cooperation of elongated slots 80 in the slide plate 24 and rivets 81 passed therethrough and fixed to the bar 77, the rivets 81 maintaining the bar 77 assembled with the plate 24.

From the foregoing description taken in connection with the accompanying drawings, it will be readily apparent to those skilled in the art to which an invention of the character described appertains, that I provide a novel and improved binder especially adapted for use with visible record systems, and in which the shifting of the prongs to staggered relationship is effected in an extremely simple and efficient manner.

What I claim as my invention is:

1. In a loose leaf binder adapted to contain record leaves, two series of impaling prongs having their ends normally engaged to form binder rings, means for mounting and guiding the series of impaling prongs for movement away from each other to permit removal and addition of record leaves, means mounting the impaling prongs of one series for tilting movement to stagger their ends with respect to the impaling prongs of the other series to effect longitudinal shifting of said leaves with respect to each other, and means for simultaneously tilting the prongs of said first series.

2. In a loose leaf binder adapted to contain record leaves, two series of impaling

prongs having their ends normally engaged to form retaining rings, means for mounting and guiding the series of impaling prongs for movement away from each other to permit removal or addition of record leaves, means mounting the prongs of one series for tilting movement about axes extending transversely of the binder, and means for simultaneously moving all of the 10 prongs of said series to tilt the same about said axes to stagger the ends of said series of prongs with respect to the prongs of the other series.

3. In a loose leaf binder of the character described, a base, two series of impaling prongs supported from said base and having their ends normally engaged to form binder rings, a sidewise shiftable element carrying the prongs of one series for sidewise movement toward and away from those of the other, individual means for tiltably mounting the prongs of said one series upon the sidewise shiftable element, and a single means movably supported from said element 25 and engageable with said individual means for effecting tilting of the prongs of said series to stagger their ends with respect to the prongs of the other series and for maintaining the same properly assembled with the sidewise shiftable element.

4. In a loose leaf binder of the character described, a base, two series of impaling prongs supported from said base and having their ends normally engaged to form binder rings, a sidewise shiftable element carrying the prongs of one series for movement toward and away from those of the other, and means for mounting the prongs of said series upon said sidewise shiftable 35 element comprising means carried by the prongs and disposed in recesses in said sidewise shiftable element, and a single means movably supported from said element and engageable with said last-named means for maintaining said prong-carried means in the recesses of the sidewise shiftable element and for simultaneously tilting the prongs of said series to stagger their ends with respect to the prongs of the other series.

5. In a loose leaf binder of the character described, a base, two series of impaling prongs supported from said base and having their ends normally engaged to form binder rings, an element for carrying the prongs of one series for movement toward and away from the prongs of the other series, means mounting the prongs of the first series upon said element comprising enlargements carried by the inner ends of the prongs of said series and received in recesses in said element, a single means movably supported from said element and engageable with said prong-mounting means for maintaining the enlargements at the inner ends of the prongs in their respective recesses and for simulta-

neously tilting the prongs of said series about their mountings to stagger their outer ends with respect to the prongs in the other series, and cooperating means carried by the prong enlargements and the means for shifting the 70 prongs for normally holding the prongs in alignment with the prongs of the other series.

6. In a loose leaf binder of the character described, a base, two series of impaling prongs supported from said base and having their ends normally engaged to form binder rings, a sidewise shiftable element carrying the prongs of one series, means mounting the prongs of said series upon said sidewise 75 shiftable element for tilting movement about axes transversely to the binder, and means movably supported from said element and engageable with said last-named means for simultaneously tilting all of the prongs in 80 said series to stagger their ends with respect to the prongs of the other series.

7. In a loose leaf binder of the character described, a base, two series of impaling prongs supported from said base and having their ends normally engaged to form binder rings, a sidewise shiftable element carrying the prongs of one series for movement toward and away from those of the other series, means for tiltably connecting the inner ends 90 of the prongs of said first series with the sidewise shiftable element, and means movably supported from said sidewise shiftable element for simultaneously tilting the prongs of said series to and from a position 95 with their outer ends in staggered relation to those of said other series.

8. In a loose leaf binder of the character described, a base, two series of impaling prongs supported from said base and having their ends normally engaged to form binder rings, transversely movable means for supporting the impaling prongs, the supporting means for one series of prongs including a plate member having a plurality of recesses, means having the inner ends of the prongs of said series fixed thereto and received in said recesses to tiltably mount the prongs for movement to and from a position with their outer ends out of alignment with the 105 ends of the prongs of the other series, means for maintaining the prong-carrying means disposed in their respective recesses, and for simultaneously moving the prongs of said 110 first series.

9. In a loose leaf binder of the character described, a base, two series of impaling prongs supported from said base and having their ends normally engaged to form binder rings, transversely movable means for supporting the impaling prongs, the means for supporting the prongs of one series including a member having a plurality of recesses, individual plate members tiltably disposed in said recesses and having the inner ends of 115 120 125 130

- the prongs of said series secured thereto, means for normally locking the individual plate members in their positions maintaining the prongs carried thereby in alignment with the prongs of the other series or for freeing the prong-carrying plate members for rocking movement to tilt the outer ends of the prongs carried thereby out of alignment with the prongs of the other series.
10. In a loose leaf binder of the character described, a base, two series of impaling prongs supported from said base and having their ends normally engaged to form binder rings, transversely movable means for supporting the series of impaling prongs, the supporting means for one series including a plate member having a plurality of recesses, members disposed in said recesses, means rockably mounting said members in their respective recesses, the inner ends of said series of prongs being secured to the rockably mounted members, a movable member covering the prong-carrying members, and means whereby the movable member when in one position secures the prong-carrying members against rocking movement to maintain their prongs in alignment with the prongs of the other series and when moved to its other position rocks the prong-carrying members and consequently the prongs carried thereby to stagger their ends with respect to the prongs of the other series.
11. In a loose leaf binder of the character described, a base, two series of impaling prongs supported from said base and having their ends normally engaged to form binder rings, transversely movable means for supporting the impaling prongs, the means for supporting the prongs of one series including a plate member having a plurality of recesses, members fixed to the inner ends of the prongs of said series and disposed in the plate member recesses, means rockably mounting said prong-carrying members in the recesses, a movable member covering the prong-carrying members and maintaining them in their recesses, and cooperating means carried by said prong-carrying members and the movable member for rigidly locking the prong-carrying members against rocking movement when in one position and for tilting the prong-carrying members about their rockable mountings upon being moved to its other position.
12. In a loose leaf binder of the character described, a base, two series of impaling prongs supported from said base and having their ends normally engaged to form binder rings, transversely movable means for supporting the impaling prongs, means mounting the impaling prongs of one series from its supporting means to permit tilting of the impaling prongs about axes transverse to the binder to stagger their outer ends with respect to the prongs of the other series while

securing said first mentioned series of impaling prongs against movement axially of the transverse axes about which they are tilttable, and means for simultaneously tilting said series of impaling prongs about 70 their mountings.

In testimony whereof I have hereunto affixed my signature.

ADOLPH G. LOTTER.
